STEAMING AND PRESSING DEVICE

George A. Schaeffer, 43 Oak Rest Lane, North Babylon, N.Y., and Neil White, 65-50 Wetherole St., Rego Park, N.Y.

Filed June 21, 1965, Ser. No. 465,379
16 Claims. (Cl. 38-141)

This invention relates to fabric material treating devices and more particularly to portable devices for steaming, pressing or simultaneously steaming and pressing relatively small and particularly shaped portions of fabric garments to improve the appearance thereof.

Situations frequently arise in the merchandising and display of fabric garments, such as men's and women's shirts and blouses, where it is desirable to steam, press or steam and press localized portions of such garments, such as the collars and cuffs thereof, to improve the appearance of these portions and thereby present a totally acceptable appearance to the garments. For example, when shirts and blouses are manufactured and thereafter packaged for display by the manufacturer, or are received in bulk packages from the manufacturer to be repackaged for display by the retailer, it frequently occurs that the pointed collars of men's shirts and the various shaped rounded collars on women's blouses, and/or the cuffs of either, become turned or bent, either during the packaging or during shipment, with the result that these parts become creased and present an undesirable appearance upon subsequent display. Since these garments are frequently packaged in individual display packages, it is a burdensome, and in some cases impossible, task to remove a garment from the package and press it by conventional means to remove the crease. The overturned portion of the collar or cuff may be turned down by hand, but the unsightly crease in a new and otherwise perfectly pressed garment remains.

A similar problem exists in commercial laundry and dry cleaning establishments in which, when shirts and blouses are laundered or dry cleaned as the case may be, a collar or cuff becomes inadvertently bent or creased and this condition is not discovered until the garment is packaged or otherwise prepared for delivery to the customer. Such an unsightly crease in the garment, particularly a white shirt or light colored blouse where such a crease would be readily apparent, has a deleterious effect upon the customer's opinion of the quality of the launderer's workmanship.

Conventional pressing equipment is highly unsuited to removing these relatively small but unsightly and undesirable appearance defects in new or freshly cleaned or laundered garments. For one thing, such equipment requires that the garment be unfolded and placed in the pressing equipment. This procedure is costly, and adds to the wear and tear on the garment. In addition, it is frequently possible to correct the defect and remove the crease merely by the application of a small amount of steam directly to the crease, without resorting to actual pressing of the material. However, again most conventional steaming and pressing equipment is of such a nature that the garment must be removed from the package, unfolded, and placed in the equipment, and then repackaged. And such portable steaming devices as are known are either not capable of supplying superheated dry steam to the garment, which is a necessity in the case of various materials which are spotted or otherwise injuriously affected by being wetted, or they are not capable of applying a hot pressing surface to the relatively small and often difficult to reach creased surface without first unfolding the garment. There is no heretofore known portable device which is suitable for either steam-

ing or steaming and pressing small inaccesible portions of a folded garment.

It is, therefore, a principal object of this invention to provide a device for steaming, pressing or simultaneously steaming and pressing particularly shaped portions of garments, such as collars and cuffs, which avoids the foregoing and other disadvantages of prior art equipment and devices.

Another object of the present invention is to provide a device of the character described in which the same element performs both the steaming and pressing functions, whether individually or simultaneously.

Still another object of the present invention is to provide a device of the character described in which the steam is distributed and applied to the surface of the material being pressed through the pressing surface of the element employed to effect the pressing.

Another object of the present invention is to provide a device of the character described which is adaptable to press a variety of shaped portions of garments by the application thereto of differently shaped removable pressing elements.

Still another object of the present invention is to provide a device of the character described in which steam from an external source is superheated and thoroughly dried before it is applied to the material being pressed.

A still further object of the present invention is to provide a device of the character described which provides accurate control over the quantity and pressure of the steam being delivered to the material.

An important feature of the present invention is the provision of means whereby the same heating element utilized to superheat the steam received from an external source is also utilized to heat the pressing surface of a material pressing element attached to the device.

Another feature of the present invention is the provision of means for assuring a proper circulation of the steam from an external source around and along a heating element so that only dry superheated steam will be discharged onto the material being treated.

Yet another object of the present invention is to provide a device of the character described which is economical to manufacture, simple to operate and maintain and inexpensive in cost.

Other objects and advantages of the present invention will become apparent from the following detailed description of a preferred embodiment of the invention when considered in conjunction with the accompanying drawings in which:

FIGURE 1 is a longitudinal sectional view through the device of the present invention with one form of steaming and pressing element applied thereto;

FIGURES 2 and 3 are longitudinal views of alternative forms of steaming and pressing elements adapted to be utilized with the device of the present invention;

FIGURE 4 is a sectional view on the line 4-4 of FIG. 3; and

FIGURE 5 is a longitudinal sectional view of an alternative form of steam circulating means in the heating chamber.

Referring now to the drawings and particularly to FIGURE 1, the steaming and pressing device 10 is seen to comprise a substantially rectangular body portion 12 which is provided with an axial bore 14 extending therethrough. One end 16 of the bore 14 is threaded to removably but sealingly receive the correspondingly threaded end 18 of an elongate, substantially cylindrical cartridge-type heating element 20, the heating element 20 extending through the bore 14 and having a portion which projects beyond the body portion 12 by a substantial distance, such as three times the length of the body portion as in the illustrated embodiment. As will be more

clear hereinafter, the amount by which the heating element projects beyond the body portion 12 is determined by the amount of heat necessary to both superheat steam circulating around the heating element and to heat a pressing element to a proper pressing temperature.

The heating element 20 has a smaller diameter than the internal diameter of the bore 14, except for the threaded portions. Thus there is provided with the body portion 12 an annular space 22 between the heating element 20 and the interior surface of the bore 14, which forms part of a superheating chamber as will more clearly appear hereinafter.

The body portion 12 is provided with a passageway 24 and a connecting passageway 26, the latter communicating with the annular space 22. The passageways 24 and 26 are part of a conduit means 26' which connects the annular space 22 with an external source of steam whereby steam from such source may be admitted to the annular space 22. In the illustrated embodiment, this source comprises a steam generator 28 from which the passage of steam is controlled by a suitable valve mechanism such as the solenoid operated valve 30, the latter being controlled by a foot operated switch 32. A suitable Teflon or other flexible hose 33 connects the valve mechanism with the conduit means 26' to provide steam to the annular space 22 and also facilitates manipulation of the device to enhance portability thereof.

In order to direct steam to the area of a garment being treated, and to simultaneously press this area if desired, the device is provided with a material pressing element 34 which is of hollow cylindrical construction and fits over the portion of the heating element 20 which projects beyond the end of the body portion 12, and is connected to the body portion 12 at the end 36 thereof remote from the end having the threaded portion 16 of the bore 14. In the illustrated embodiment, the connection of the pressing element 34 to the body portion 12, and the removal thereof and replacement of different pressing elements, is facilitated by a short tubular connector 38, threaded engaged with the body portion 12, and to which the pressing element 34 is connected by means of the nut 40. If desired, however, the pressing element 34 and the connector 38 may be an integral element.

It will be observed that both the pressing element 34 and the connector 38 have an internal diameter which is larger than the diameter of the heating element 20, and substantially the same as the bore 14, thereby providing an annular space 42 which forms a continuation of the annular space 22. Thus the two annular spaces 22 and 42 together constitute a heating chamber extending for the full length of the heating element 20 in which the moist steam from the generator 28 is superheated and dried so that only dry steam is applied to the material being treated. The heating chamber is annular and substantially uniform in cross-section throughout its length to assure an even superheating and drying of the moist steam passing therethrough.

As previously stated, it is one of the objects of this invention to both steam a portion of a garment and to simultaneously press it with the same element, thereby eliminating the necessity of a specially shaped pressing element for pressing the particular portions of garments to which the present invention is suited and an auxiliary device for supplying the steam. To this end, the pressing element 34 terminates outwardly in a shaped end or tip 44, which, in the case of the pressing element 34, is pointed and conical in cross-section and is particularly adapted for pressing creases in the pointed collars of men's shirts. The pressing tip 44 is provided with a plurality of apertures 46 through which the superheated steam from the chamber 22-42 is applied to the material being pressed.

Thus it is seen that by the construction described, the heating element 20 functions both to superheat the steam passing through the heating chamber 22-42 and to heat

the pressing element with tip 44 to a proper operating temperature. To facilitate the latter, the pressing tip 34 is made from a suitable high heat-conducting metal, the thermal coefficient of which determines the amount by which the heating element 20 should project beyond the end of the body portion 12; also, the length of the pressing element and the shape thereof are factors to be considered in selecting a proper size and capacity heating element.

The device is provided with a suitable thermostatic control element 48 which controls the temperature of the heating element 20 in accordance with the nature of the material being pressed, it being understood that the minimum temperature at which the pressing element operates is nevertheless sufficient to superheat the steam passing through the chamber 22-42 to the desired dry condition.

In order to assure the achievement of this condition during the passage of the steam through the chamber 22-42, provision may be made for causing the steam to circulate through the chamber and around the heating element 20 in intimate contact therewith. This is accomplished in one embodiment of the invention by the provision of one or more spiral grooves 50 formed in the heating element 20 which tend to direct the steam around the heating element in a helical path. Other means may be provided for achieving the same result, such as similar grooves formed on the inner surface of the connector 38 and the pressing element 34. FIG. 5 illustrates another modification of means for causing the steam to circulate around and over the heating element 20, this being the provision of a sleeve 50 adapted to fit snugly within the connector 38 and pressing element 34 and having a plurality of tabs 52 struck inwardly from the wall of the sleeve, thereby providing an obstruction or barrier to the free flow of steam through the heating chamber and at the same time providing apertures 54 in the sleeve to facilitate the passage of heat from the heating element 20 to the pressing element 34. The use of this construction requires a reduction in the diameter of the heating element 20.

Means are provided for controlling the rate of flow of steam through the device independently of the valve mechanism 30, the latter being merely a shut-off valve which permits or prevents steam flow. This means is illustrated as being a needle valve 56 disposed in the passageway 24 and cooperating with a valve seat 58 formed therein. The valve 56 is adjusted relative to the seat 58 by turning a threaded shank 60 received in a threaded bore 62 formed in the body portion 12 in axial alignment with the passageway 24. A spring 64 maintains the needle valve in any desired position to which it is set by turning the knob 66.

The device of this invention is intended to be relatively portable and to be hand held when in use, so that the pressing element 34 may be directed into relatively inaccessible places within the garment to steam or steam and press such places without the necessity of unfolding the garment. To this end, the operating parts of the device are partially encased in a housing having a central holding portion 68, an outwardly flared closed end 70 and an outwardly flared open end 72. The open end 72 is closed by a suitable cap or cover 74 which is removable to provide access to the interior of the housing, and which is provided with an aperture 76 which snugly surrounds the connector 38 and an aperture 78 through which the shank 60 of the needle valve 56 extends. The housing may also be provided with scales (not shown) with which a knob 80 cooperates to indicate the temperature setting of the thermostatic control 48 and with which the knob 66 cooperates to indicate the setting of the needle valve 56. In addition, the interior of the housing is preferably filled with a suitable insulating material 82 to maintain the housing sufficiently cool to hold over long periods of use.

As indicated hereinabove, the pressing element 34 is

removable, either directly from the body portion 12 or from the connector 38, to permit replacement thereof with other pressing elements for pressing differently shaped portions of the shirts or blouses. For example, the pressing element 84 illustrated in FIGURE 2 is particularly suitable for steaming or pressing the various shapes of rounded collars generally found on women's blouses. This pressing element comprises a generally cylindrical portion 86 which terminates outwardly in a rounded end portion 88. The super-heated steam is discharged through a plurality of apertures 90 arranged in at least one row extending substantially the length of the cylindrical portion 86 and halfway around the rounded end portion 88.

FIGURES 3 and 4 illustrate another embodiment of pressing element 92 which is particularly suitable for pressing or steaming the flatter or broader portions of the garments such as the cuffs. This pressing element has a somewhat triangular shaped tip 94 which diverges outwardly of the pressing element, the tip 94 having a pressing surface 96 which is disposed at an obtuse angle to the longitudinal axis of the pressing element 92 when measured from within the pressing element. The super-heated steam is discharged through a plurality of apertures arranged in any desired pattern such as the rows illustrated.

It is seen from the foregoing description and accompanying drawings that there is provided a steaming or steaming and pressing device which avoids the above-mentioned disadvantages and achieves the foregoing objects. It is to be understood that the invention is not to be limited to the embodiments thereof described and illustrated, which are merely illustrative of the principle of the invention and which are susceptible to modification of size, form, location and arrangement of parts, but rather is intended to cover all such modification and equivalents as are deemed to be within the scope of the appended claims.

We claim:

1. A steaming and pressing device comprising
  - (A) a body portion having an axial bore therethrough,
  - (B) an elongate electric heating element mounted in one end of said bore and projecting therethrough and having a portion which extends outwardly of said body portion a substantial distance, said heating element having a diameter less than the diameter of said bore to define an annular space therebetween,
  - (C) conduit means in said body portion communicating with said annular space and including means connecting with an external source of steam,
  - (D) an elongate hollow fabric material pressing element connected to said body portion at the other end of said bore and surrounding said outwardly extending portion of said heating element, said pressing element having an internal diameter larger than the diameter of said heating element to define an annular space therebetween which forms an extension of the annular space within said body portion, both said annular spaces forming a chamber within which steam from said external source is superheated and thus rendered free of moisture, and
  - (E) means adjacent the outermost end of said pressing element presenting a material pressing surface and for discharging said superheated steam onto the material being treated whereby said material may be steamed or simultaneously steamed and pressed.
2. A steaming and pressing device as set forth in claim 1 wherein said heating element is removably mounted in said one end of said body portion and in sealing relationship therewith.
3. A steaming and pressing device as set forth in claim 1 wherein said heating element is cylindrical and wherein said pressing element has an internal diameter substantially equal to that of said bore whereby said heating chamber is of substantially uniform cross-sectional configuration throughout its length.
4. A steaming and pressing device as set forth in claim 1

wherein said pressing element is removably connected to said body portion to permit removal thereof and replacement with another pressing element.

5. A steaming and pressing device as set forth in claim 1 wherein said means presenting said material pressing surface and for discharging said superheated steam comprises a shaped tip formed on the outermost end of said pressing element, and a plurality of apertures provided in said tip and terminating outwardly in said pressing surface.

6. A steaming and pressing device as set forth in claim 5 wherein said tip is conical and terminates in a point, and said apertures are arranged in at least one row extending substantially the entire length of said conical tip.

7. A steaming and pressing device as set forth in claim 5 wherein said tip comprises a substantially cylindrical portion which terminates in a rounded end portion, and said apertures are arranged in at least one row extending over said cylindrical portion and at least half way around said rounded end portion.

8. A steaming and pressing device as set forth in claim 5 wherein said tip is triangular and diverges outwardly from said pressing element and has a substantially flat pressing surface disposed at an obtuse angle relative to the longitudinal axis of said pressing element, and said apertures are arranged in a plurality of rows in the area of said flat pressing surface.

9. A steaming and pressing device as set forth in claim 1 further including thermostatic control means operatively associated with said heating element for controlling the operating temperature of said pressing element.

10. A steaming and pressing device as set forth in claim 1 further including means in said heating chamber for causing the steam passing therethrough to circulate around and in intimate contact with said heating element.

11. A steaming and pressing device as set forth in claim 10 wherein said circulating means comprises at least one spiral groove formed in the surface of said heating element.

12. A steaming and pressing device as set forth in claim 10 wherein said circulating means comprises a sleeve adapted to fit snugly within said pressing element, said sleeve having a plurality of tabs struck inwardly out of the surface thereof and a plurality of apertures formed in said surface by striking out said tabs.

13. A steaming and pressing device as set forth in claim 1 further including valve means in said conduit means, said valve means being adjustably carried by said body portion for controlling the rate of flow of steam through said conduit means.

14. A steaming and pressing device comprising

- (A) an elongate housing having opposite end portions and an intermediate handle portion,
- (B) a body portion having an axial bore therethrough mounted in one end of said housing,

- (C) an elongate electric heating element mounted in one end of said bore and projecting therethrough and having a portion which extends outwardly of said body portion and beyond said one end of said housing a substantial distance, said heating element having a diameter less than the diameter of said bore to define an annular space therebetween,
- (D) conduit means in said body portion communicating with said annular space and including means extending outwardly of said housing and connecting with an external source of steam,

- (E) an elongate hollow fabric material pressing element extending into said housing and connected to said body portion at the other end of said bore and surrounding said outwardly extending portion of said heating element, said pressing element having an internal diameter larger than the diameter of said heating element to define an annular space therebetween which forms an extension of the annular space within said body portion, both said annular spaces forming a chamber within which steam from said external source is superheated and thus rendered free of moisture, and

ing a chamber within which steam from said external source is superheated and thus rendered free of moisture, and

(F) means adjacent the outermost end of said pressing element presenting a material pressing surface and for discharging said superheated steam onto the material being treated whereby said material may be steamed or simultaneously steamed and pressed.

15. A steaming and pressing device as set forth in claim 14 wherein said pressing element is connected to said body portion by means of a connector member extending through said one end of said housing and secured to said body portion, said pressing element being removably connected to said connector member outwardly of said housing.

16. A steaming and pressing device as set forth in claim 14 wherein said one end of said housing is closed by a removable cap.
